DEHYDRATING SYSTEM

Joseph M. Hall, Chicago, Ill.

Application April 14, 1938, Serial No. 201,977

11 Claims. (Cl. 159—4)

This invention relates to dehydrating or desiccating systems and more particularly to the type of apparatus in which a substantially closed heating medium circulating system is employed.

One of the objects of the invention is the provision of a new and improved dehydrating device in which the waste heat is reduced to a minimum.

Another object of the invention is the provision of a new and improved system of concentrating and desiccating liquid products and of collecting the dehydrated product.

A further object of the invention is the provision of a new and improved dehydrating apparatus having novel means for reusing the heating medium during the operation of the apparatus.

A still further object of the invention is the provision of new and improved dehydrating chamber and means for removing the desiccated material therefrom.

Another object of the invention is the provision of a new and improved system or method of dehydrating material, together with a novel method of collecting or causing the desiccated material to be deposited in a collector or depository.

A further object of the invention is the provision of a new and improved dehydrating apparatus that is simple in construction, efficient in operation, comparatively inexpensive to install and that is composed of few moving parts.

Other and further objects and advantages of the invention will appear from the following description, taken in connection with the accompanying drawings, in which—

Fig. 1 is a side elevation of the apparatus shown more or less diagrammatically;

Fig. 2 is a vertical section through the dehydrator chamber, with parts broken away;

Fig. 3 is a section on the line 3—3 of Fig. 2 showing the parts on an enlarged scale;

Fig. 4 is a plan view of the dehydrator chamber;

Fig. 5 is a section on the line 5—5 of Fig. 2;

Fig. 6 is a vertical section of the primary boiler or evaporator;

Fig. 7 is a vertical section of the secondary boiler or evaporator;

Fig. 8 is a vertical section of the secondary boiler or evaporator taken at right angles to that shown in Fig. 7; and

Fig. 9 is a vertical section through the spray head.

55 In dehydrating products on a commercial

scale, it is common practice to use artificial heat for evaporating the moisture and ordinarily a great number of thermal units are discharged into the air in the form of sensible or, in some instances, latent heat or heat of vaporization. 5 Such a process is expensive and in many instances all but prohibitive, especially where the moisture is evaporated at atmospheric pressure and the vapor discharged directly into the air.

The present invention seeks to remedy these 10 difficulties by the provision of means whereby the moisture in the product is evaporated at sub-atmospheric pressure and the latent heat of vaporization utilized to further evaporate moisture from the product preparatory to dehydrating or desiccating the product.

Furthermore, the present invention contemplates recirculating portions of the heated air so as to utilize to as great an extent as possible the heat applied to the air, thereby effecting an 20 economy in the use of fuel.

A portion only of the air may be recirculated because the moisture absorbed in the dehydrator chamber is not all condensed in the boilers and for that reason fresh air is continually introduced into the system for dehydrating or desiccating the product in the dehydrating chamber, 25 as will presently appear.

Referring now to Fig. 1 of the drawings, the reference character 10 designates the apparatus 30 in general which comprises a furnace 11, an air heater 12, a principal or primary boiler or evaporator 13, an auxiliary or secondary boiler or evaporator 14, a liquid reservoir 15, a condenser 16, a vacuum pump 17, a dehydrating chamber 35 18, a spray head or nozzle 19 and the centrifugal air separator and collector 21.

The furnace 11 is provided in its forward portion with a conventional combustion chamber 22 that is separated from the remainder of the furnace chamber by a baffle 23. The baffle is provided with an opening 24 and the size of this opening may be varied at will by the insertion or removal of layers of firebrick 25, as desired. 40 The upper portion of the furnace 11 has the air heating mechanism 12 mounted therein. This mechanism comprises a plurality of horizontally arranged tubes 26 having their ends in communication with the headers 27 and 28. The header 28 has connected thereto a blower 29 operated by a suitable motor 31 for forcing air through the heating tubes 26.

The header 27 has connected thereto a pipe or passage 32 for conducting the heated air to 55

the dehydrating chamber 18, as will presently be described.

The baffle 23 extends upwardly among the tubes 26 and is adapted to cause the heated gases 5 to pass upwardly around the tubes 26 for heating the air passing through said tubes.

Heat may be supplied to the furnace in any suitable manner. As shown, a conventional oil burner 33 is provided for this purpose. Oil is 10 then supplied to the burner 33 by a pipe 34 in the usual manner. Suitable doors 35 and 36 are provided in the side of the furnace to permit access to the same.

Suitable means are provided for concentrating 15 the product preparatory to dehydrating the same. In the form of the device selected to illustrate one embodiment of the invention, a plurality of boilers or evaporators are employed. As shown, two are used, but it is understood that 20 this is by way of example only as additional boilers may be employed, if desired. These two boilers, for convenience of description, will be referred to as the primary or principal boiler and secondary or auxiliary boiler.

25 The primary boiler 13 comprises an upper section or vapor chamber 37 and a lower section 38, Fig. 6. The lower section 38 has a header 39 secured below the same and this header is in communication with the upper section 37 through a series of pipes 41 secured in a partition plate 42 between the upper and lower sections. The lower ends of the tubes 41 are secured in a partition plate 43 between the lower section 38 in the header 39. The primary boiler is adapted to be 30 supplied with milk or other liquid or semi-liquid product from the reservoir 15 through a suitable pipe or passage 44 which is controlled by a valve 45, Fig. 1.

The upper end of the primary boiler or evaporator 13 is provided with a manhole 46, Fig. 6, 40 having an upwardly extending cylindrical portion 47 provided with an outwardly extending peripheral flange 48. The manhole 46 is provided with a closure 49 hinged as at 51 and is provided with a latch 52 for clamping the same in position. The parts are so constructed that the closure is 45 air-tight. The closure 49 may, if desired, be provided on its upper portion with a sight opening 53 which is closed by a glass plate 54.

50 During the operation of the device, the milk or other liquid product is supplied to the primary boiler so that the level will be slightly above the partition 42.

Suitable means are provided for evaporating 55 the liquid in the primary boiler. In the form of the device selected to illustrate one embodiment of the invention, this is accomplished by passing heated gases from the furnace 11, Fig. 1, through the lower section of the primary boiler 60 and simultaneously reducing the pressure in the upper portion of the boiler. As shown, the back wall of the furnace 11 is provided with an opening in which one end of a conduit 55 is secured, its other end being secured in the wall 56 of the lower section of the boiler 13. The heated gases 65 pass around the tubes 41, Fig. 6, and impart their heat to the liquid contained in the tubes and these gases are exhausted from the lower section through the wall 56 and through a conduit 57 into the secondary boiler, as will presently be described.

The secondary boiler or evaporator 14, Figs. 7 and 8, is constructed somewhat similar to the primary boiler but with certain exceptions as 75 will now be described.

This boiler comprises an upper section 58, a lower section 59 and a header section 61. The upper section 58 is provided with a flanged opening 62 having a closure 63 provided with a sight opening closed by a glass plate 64 as in the 5 previous construction.

The lower section 59 of this boiler has an inner cylindrical portion 65 and an outer annular chamber 66, surrounding the cylindrical portion 65. The inner section 65 has an outer wall 67 10 concentric with the wall 68 of the lower section 59 of the boiler and has end plates 69 and 71 which are provided with openings in which are secured the pipes 72. The pipes 72 place the upper section 58 of the boiler in communication 15 with the header 61. The outer annular portion 66 has a partition 60 between it and the upper portion and a partition 70 between it and the header 61. Tubes 80 place the header 61 in communication with the upper section 58. 20

The space 73 among the tubes 72 of the inner cylindrical portion 65 of the lower section of the boiler 14 is placed in communication with the upper section of the primary boiler 13 through the pipe 74, as shown more clearly in Figs. 1 and 25 7 of the drawings. The pipe 74 is attached to the upper section 37 of the boiler 13 adjacent its upper end and to the upper portion of the wall of the cylindrical portion 65 so that steam and vapor may be conducted from the upper section of the boiler to the inner portion 65 of the lower section for heating the pipes 72 for further evaporating the liquid condensate contained in those tubes. The concentrate from the primary boiler is transferred to the secondary boiler 30 through the pipe 75 and the flow is controlled by a suitable valve 76 in the pipe 75.

In order to materially increase evaporation of the product, during the operation of the device, suitable means are provided for maintaining the 40 pressure within said boilers at sub-atmospheric and in order to insure the flow of the liquid product from the primary to the secondary boiler, means are provided for maintaining the pressure within the secondary boiler below that in the 45 primary boiler as will now be described.

The lower end of the inner or cylindrical portion 65, Fig. 7, of the lower section of the secondary boiler is connected to the vacuum pump 17 by means of pipes 77 and 78, Figs. 1 and 7. 50 The pipe 77 is provided with a valve 79 which may, if desired, be made automatic to open at a pre-determined pressure. The parts are so adjusted that the pressure in the upper section of the primary boiler 13 is below that of the atmosphere 55 but considerably above that in the secondary boiler 14 whereby vapor and the concentrate will be caused to flow from the first to the second boiler. By manipulating the valve 79, the pressure within the inner portion 65 of the lower 60 section of the secondary boiler may be held at any desired and predetermined amount and this in turn will control the pressure within the upper section of the primary boiler 13 through the pipe 74. 65

The upper section of the secondary boiler is connected by a pipe 30 with the condenser 16 and through the condenser to the pump 17 whereby a low pressure is maintained in the upper section 58 of the secondary boiler. The pressure within the upper portion of the primary boiler is maintained higher than that within the cylindrical portion 65 thus allowing the vapor to readily pass over from the primary to the secondary boiler. The upper section of the secondary boiler 75

is maintained at a lower pressure than the upper section of the primary boiler whereby the concentrate readily passes from the primary to the secondary boiler, where it is further concentrated.

As an example of the working conditions, the pressure within the boiler 13 may be held at twenty inch vacuum by manipulating the valve 79 while the pressure within the secondary boiler 14 exterior of the portion 65 may be held at a vacuum of twenty-eight inches. The temperature of the air from the furnace 11 entering the primary boiler may, for instance, be around 700° F. while the temperature of the heated gases supplied to the secondary heater 14 may be materially lower due to the absorption of heat by the liquid product causing the latter to boil. The air may leave the second boiler around 180 to 190 degrees. These temperatures are given by way of example only and it is understood they may be varied within wide limits.

After the heated gases supplied from the furnace to the primary boiler through the passage 55 have passed through the primary boiler, a considerable portion of the heat is imparted to the liquid to be evaporated and then these gases pass through the passage 57 to the outer portion of the lower section of the secondary boiler. The fan or blower 40 exhausts the heated gases, which have their temperature lowered still further in passing through the secondary boiler and will finally emerge into the discharge passage 81 of the fan or blower 40 at a greatly reduced temperature.

35 The combustion gases, on passing from the secondary boiler 14, are conducted through the conduit 82 into the centrifugal fan 40 and from thence they are discharged into the rear end of the firebox 22 through the conduit 81 and a portion of them are caused to be recirculated through the boilers in a partially closed system and a portion discharged through the discharge pipe 83. Since air is being continuously introduced into the system, air or the combustion gases must be continuously discharged therefrom. Consequently, a portion of these gases is discharged into the atmosphere through a discharge conduit 83 as they circulate through the conduit 81. The conduit 83 has a suitable valve 84 for controlling the discharge of these gases.

Suitable means are provided for dehydrating or desiccating the concentrated liquid product. In the form of the construction shown, a dehydrator chamber 18 is provided for this purpose. This chamber may be of any suitable form but in the construction shown, it is cylindrical and has an upwardly sloping top wall 85, Fig. 1, which terminates in a horizontal portion 86 through which the liquid product from the second boiler 14 is delivered to the interior of the dehydrator.

The lower portion of the dehydrator tapers inwardly and downwardly as at 170 and has a cone deflector 180 rising upwardly within said tapered portion whereby inner and outer sloping walls are provided for directing the desiccated material downwardly into an air channel or trough, as will presently appear.

70 The evaporator or dehydrator chamber 18 is provided, on its upper portion, with a distributor mechanism 19 comprising a spray mechanism or atomizer 87 for reducing the concentrated liquid product delivered through the pipe 88 to fine particles and discharging the same into a heated

current of air within the dehydrating chamber, as will presently appear.

The spray mechanism 87 comprises a casing 89, Fig. 9, which is rigidly mounted on the top wall of the evaporating chamber 18 and has a complementary section 91 which is hinged thereto as at 92 and a latch mechanism 93 is adapted to secure the two sections together to form a chamber 94 within which a centrifugal blower 95 is adapted to rotate.

10 The blower 95 is of the usual or any well known construction having the spiral blades 96 for discharging air radially into the space or passage 97 extending about the fan or blower 95. The air is discharged through a passage formed by a partition 100, into a hollow drum or cylindrical member 98 which is secured to the central portion of the casing 89 and extends downwardly into the dehydrator 18 as is more clearly shown in Fig. 9 of the drawings. The blower 95 is rigidly attached to a vertical spindle 99 which extends downwardly into the interior of the dehydrating chamber. This spindle is hollow for conducting the liquid product to the header as will presently appear.

15 The spindle 99 is adapted to be rotated by a motor 101, the rotor 90 of which is rigidly connected to said spindle. The casing 102 for the motor is provided with an air passage or jacket 103 which extends about the motor for cooling 30 the same. The air enters the passage 103 through an opening 104 which has an adjustable closure 50 and passes around the motor and through the passage 105 into the chamber 106 just above the blower 95 and is then drawn axially 35 into said blower and discharged radially into the passage 97 as described above. From the passage 97, the air is forced along the passage 101 into the drum 98 for cooling the bearings 128 and for preventing back pressure in the head, 40 as will presently appear.

The upper end of the spindle 99 extends into a stationary casing or hollow casting 108 in which a suitable gland 109 is provided for making a liquid-tight joint between the spindle and the casting as shown more clearly in Fig. 9 of the drawings. The upper end of the casting 108 is provided with a screw-threaded cap 111 within which is mounted a spring 112 which seats against an element 113 of the gland. By adjusting the cap 111, the tension on the gland element may be varied.

45 The casting 108 is provided with a lateral extension 114 having a passage 115 closed at its outer end by a plug 116. The lateral extension 55 is provided with a nipple 117 to which the lower end of the conduit or pipe 88 is adapted to be attached. Mounted within the passage 115 is a control valve 118 for controlling the supply of liquid product to the passage in the spindle 99. 60

65 Suitable anti-friction bearings 119 and 121 may be provided for the spindle 99. The drum 98 is rigidly attached at its upper end to the blower or fan casing 89 and its lower end is closed by a plate 122 having an axial opening 123 therein through which the spindle 99 extends. The plate 122 is secured to a flange 124 on the cylindrical member 98 as by means of the cap screws 125. A sleeve 126 of insulated material is provided for the cylindrical member 98, as shown in Fig. 9 of the drawings, for preventing the liquid product in the bore of the spindle from becoming injuriously affected with the hot air introduced around the sleeve for dehydrating the atomized material, as described below.

Secured in the rabbet in the lower end of the cylindrical member 99 by the plate 122 is a casting 127. The casting 127 is provided with a recess in which is mounted an anti-friction bearing 128 for the lower end of the spindle. A pipe 129, secured in the casting 127, is adapted to supply the necessary amount of lubricant to the bearing 128. The plate 122 and casting 127 are provided with a plurality of openings 131 through 10 which the air from the blower 95 is discharged.

Mounted on the lower end of the spindle 99 is the spray head 132 which comprises a cone member 133 having its apex attached to the spindle 99 whereby the head rotates with said 15 spindle. The apex of the cone member is provided with air passages 134 for admitting a portion of the air discharged through the passages 131 for preventing back pressure in the cone member 133 when the same is in operation since 20 the high speed rotation of the cone member tends to create a partial vacuum in this member.

The lower end of the spindle 99 is provided with a cap 135 having downwardly and outwardly extending openings 136 through which the 25 liquid product flowing through the axial opening 136 in the spindle 99 is discharged. This liquid is withdrawn from the boiler 14 and forced through the pipe 88 and passage 136 by a pump 137, Fig. 1, operated by a motor 138. The pressure of the liquid and centrifugal force of the rotating head is sufficient to cause the liquid product to be deposited on the interior surface 30 of the cone member 133 and due to the speed of this member, the liquid product will be gradually thrown outwardly onto the inner surface of the cone and will spread out in the form of a film which gradually decreases in thickness as the area of the surface expands toward the lower end of the cone member 133. The lower 35 edge of the cone member is provided with a large number of slots 139 spaced some distance apart. These slots are arranged at an angle to vertical planes through the axis of the cone member. The cone member is rotated in the direction of the arrow in Fig. 3, that is, it is rotated in such 40 a direction that the lower ends of the slots lead the upper ends thereof. Their distance apart and the angular direction of the slots are such that a vertical plane through the axis of the cone and the upper end of the advancing slot 45 will intercept the lower end of the following slot whereby all of the liquid passing downward on the inner surface of the cone member will be 50 intercepted by slots and thrown outwardly from the entire length of the edge of each slot by centrifugal force in the form of a band or ribbon of particles.

The lower portion of the cone member 133 is provided with radially extending flanges or 55 plates 141 and 142 spaced apart and having curved vanes 143 between the same, Figs. 3 and 9. The plates 141 and 142 diverge outwardly so that the vanes 143 are wider at their outer ends than at their inner ends. The lower plate 142 60 terminates outwardly of the lower end of the cone 133 and the opening is closed by a plate 144. When the plate 144 is removed, access may be had to the inner portion of the cone. If desired, the upper and lower plates 141 and 142 65 may be cast integral with the vanes 143 and with the cone 133 as shown in Fig. 9 of the drawings. The lower portion of the cone below the upper ends of the slots 139 extends downwardly 70 below the upper plate 141 but terminates above the plate 144.

The blades 143 curve sharply rearwardly at their inner ends. This is done in order to prevent spattering of the product discharged outwardly by centrifugal action of the cone when it comes in contact with the blades. These particles are traveling at the speed of the slots when they are thrown tangentially from the cone. This speed is lower than the vanes 143 so by curving the vanes rearwardly they may pick up these particles and gradually increase their speed, as it were. The band or ribbon of particles discharged from the slots 139 is spread evenly across the inner ends of the blades 143 and the centrifugal force of the particles will cause them to spread across the blade as they 10 approach the outer ends thereof and since these blades increase in width toward their outer ends, the film of the liquid product on each blade will become thinner and thinner as it approaches the blade ends. The liquid material is thrown 15 from each blade in a fine ribbon-like spray. This ribbon-like spray of finely divided particles will be struck broadside by the rotating column of hot air for dehydrating the particles, 20 as will presently appear.

The head 132 may be of any convenient size and rotated at any desirable speed. It has been found that the use of a head of from sixteen to eighteen inches in diameter across the vanes 143 and rotated at a velocity of 3500 revolutions 25 per minute operates satisfactorily to reduce milk concentrate to the desired degree of fineness for desiccating the same in the dehydrating chamber 18.

Suitable means are provided for delivering a 30 strong blast of heated air across the atomized material discharged radially outwardly from the blades 143. In the form of the construction shown, the pipe 32 leading from the air heater 12 is connected to an air distributor 145 on the 35 top of the dehydrator 18. This distributor is arranged in the form of a snail about the upper end of the spindle 99 and is of gradually diminishing diameter so as to maintain a constant pressure and velocity of the air throughout the 40 length of the snail.

The top of the dehydrator is provided with an opening 146 extending about the spindle 99 and the top wall 147 of the air distributor 145 is spaced upwardly from the wall of the dehydrator so as to provide a passage 148 through 45 which air can escape from the snail passage 149 throughout its length. A sleeve 151 extends downwardly from the marginal edge of the opening 146 and has its lower end flared outwardly as shown at 152 for directing the air 50 downwardly and outwardly across the head 132, as shown more clearly in Fig. 2 of the drawings. The diameter of the sleeve 151 is such that the head 132 may be removed by lifting the same 55 upwardly through this sleeve.

A suitable cone-shaped shield 140 is mounted over the head 132 for directing the air outwardly toward the periphery of the head.

The air passing through the conduit 32 may 60 be previously heated to any desired temperature. It is found that for dehydrating milk concentrate that a temperature of around 500° F. gives satisfactory results. The air is delivered under pressure by the blower 29 and escapes 65 across the head 133 in umbrella form. This heated air is caused to rotate by the snail or circular form of the air distributor 145 and the parts are so arranged that the air will be moved 70 in the same direction as the rotation of the 75

head 133 so that the air and mist, or atomized or finely divided particles of liquid product will thoroughly intermingle whereby those particles are completely dehydrated.

5 The solid particles, after being dehydrated, will pass with the air to the bottom of the dehydrator. The bottom of the dehydrator is provided with a circular channel 153, the outer side wall of which is bent inwardly and rigidly secured 10 to the tapered wall of the dehydrator. The edge of the cone 80 extends into the channel to form a restricted slot which will permit the dehydrated material to slide down these inclined walls into the channel 153 but will be sufficiently 15 restricted to conduct the air along the channel. The channel is of gradually increasing cross-sectional area toward its discharge end.

The desiccated material, while hot, tends to 20 adhere to the trough or channel 153. It has been found that if the air flowing through the trough 153 is reduced in temperature or its velocity increased, or both, that the channel will remain practically clean.

25 Suitable means are provided for introducing cool air into the channel or trough and also for increasing the velocity of the air flowing through this channel. In the form of the construction shown, Fig. 1, a return pipe or conduit 165 is provided for conducting air from the conduit 157 to the channel 153 as indicated in Figs. 4 and 5. The conduit 165 delivers into the small end of the channel 153 as shown more clearly in Figs. 4 and 5. A suitable blast valve 166 is provided 30 in the conduit 165 for controlling the amount of air passing from the pipe 157 back to the channel.

35 Suitable means are also provided for introducing cool air into the return pipe 165. A conduit 167 is provided for this purpose. It is in communication with the conduit 165 and has mounted therein a fan 168 operated by a suitable motor 169. The intake 171 of the fan is adapted to be provided with a suitable air filter 172 so that filtered air may be introduced from the atmosphere into the pipe 167 and in turn 40 into the channel 153. A valve or blast gate 173 is provided for controlling the amount of air delivered by the fan 168 into the passage 167. By properly adjusting the valves 166 and 173, air at the required temperature and velocity 45 may be introduced into the channel 153 for maintaining the same completely free of matter adhering to the walls thereof.

50 Suitable means are provided for separating the material contained in the air in the conduit 155. The collector 21 is employed for this purpose. The collector 21 is of centrifugal type and has a casing to which the conduit 155, leading 55 from the enlarged end of the channel 153, for delivering air and solid material axially into the separator 21, is attached. The separator is operated by a suitable motor 156. The separator sucks the air and desiccated material 60 through the conduit 155 and after separating the material from the air, discharges the latter through a conduit 157 into the forward end of the firebox 22 as at 158 as shown more clearly 65 in Fig. 1 of the drawings.

70 Since the collector 21 is well known in the art and the details of which constitute no part of the present invention, it is not thought necessary to further illustrate or describe the same.

75 The solid particles, separated from the air, fall by gravity into a hopper 159 which has a

rotary discharge valve 161 controlled by a motor 162 in the usual manner.

In the operation of the device, milk or other liquid products to be dehydrated are delivered 5 from the reservoir 15 into the primary boiler 13 where the product is partially evaporated, as above described, by heated air flowing through the conduit 55. The heated gases pass into the outer annular chamber 66 and from thence into the fan 40 and back to the furnace to be mixed 10 with the heated gases therein. A portion of it escapes into the atmosphere. The vapor from the product in the first boiler is conducted to the inner chamber 65 of the second boiler for assisting in evaporating the liquid product in 15 that chamber. From the second boiler the concentrate is conducted to the atomizer within the dehydrator. Heated air from the air heater 12 is delivered over the atomizer for desiccating the atomized material. Heated air from the air heater 20 is removed by a current of air to the collector where the dehydrated material is collected and the air conducted to the furnace to aid in combustion of the fuel for 25 heating the air used in the process.

It is thought from the foregoing, taken in connection with the accompanying drawings, that the construction and operation of my device will be apparent to those skilled in the art and that changes in size, shape, proportion and details may be made without departing from the spirit and scope of the appended claims.

I claim as my invention:

1. In a dehydrating system for liquid products, 35 a primary and a secondary boiler arranged in series, means for heating said primary boiler by heated combustion gases for evaporating moisture from said products for concentrating the products, means for utilizing said combustion gases from the primary boiler and the vapor produced in the primary boiler for heating the concentrated liquid product in the secondary boiler for further concentrating the same, and means for maintaining the pressure within said secondary boiler below that of the atmosphere and 40 below that within the primary boiler.

2. In a system for dehydrating liquid products, 45 a furnace, a pair of boilers arranged in series, means for supplying liquid products to said boilers, a furnace, means for conducting heated gases 50 from said furnace through said boilers in heat exchange relationship to the liquid product within said boilers for evaporating moisture from said liquid product, means for conducting vapor produced in one of said boilers into the other boiler for assisting in heating the product contained 55 therein, and means for lowering the pressure in said second boiler below that of the atmosphere and for maintaining said pressure below that in 60 the first boiler whereby the concentrate within the first boiler will flow into said second boiler and have its boiling point lowered in said second boiler.

3. In a dehydrating apparatus, a furnace, an 65 air heater within said furnace, an evaporator for concentrating a liquid product, means for recirculating heated gases through said furnace and evaporator and for causing heated gases to flow 70 through said heater, a dehydrator, means for supplying the concentrate from said evaporator to said dehydrator, means for conducting heated air from said heater to said dehydrator for dehydrating said product, and means for conducting all of 75 said air from said dehydrator to the combustion

chamber of said furnace for causing an increased velocity of the heating fluid through said heater.

4. A dehydrator comprising a chamber, means for conducting heated air to said chamber, means for conducting a liquid product to said chamber, means for atomizing said product and for discharging the same in said dehydrator, a discharge channel extending around the lower end of said chamber in a circular path for said air and dehydrated product, and means for introducing air under pressure into said channel for increasing the velocity of the air therein.

5. A dehydrator comprising a chamber, means for conducting heated air to said chamber, means for conducting a liquid product to said chamber, means for atomizing said product and for discharging the same in said dehydrator, a discharge channel extending around the lower end of said chamber in a circular path for said air and dehydrated product, a centrifugal separator in communication with said channel, and a conduit for conducting air from the discharge of said separator to said channel for increasing the velocity of the air passing therethrough.

25 6. In a dehydrating system for liquid products, a furnace having a combustion chamber, a dehydrator, means for spraying a liquid product within said dehydrator, an air heater heated by said furnace, means for conducting air from said heater to said dehydrator and for discharging the same therein for evaporating moisture from said product, means for conducting said air from said dehydrator to said combustion chamber, evaporator means, means including a conduit for recirculating combustion gases through said combustion chamber and evaporator means, said conduit having an opening for discharging a portion of said gases from said system.

40 7. In an apparatus for dehydrating liquid products, a furnace having a combustion chamber, an air heater heated by said furnace, evaporator means, means for supplying a liquid product to said means, means for conducting heated gases from said furnace through said evaporator means and back to said furnace for evaporating moisture from said liquid product, a discharge conduit in the means for conducting the heated gases for discharging a portion of said gases therefrom, a dehydrator, means for conducting heated air from said air heater to and through said dehydrator, and discharging the same into said combustion chamber, and means for conducting said air along with said heated gases through said

evaporator for evaporating moisture from said liquid product.

8. In an apparatus for dehydrating liquid products, a furnace, a heater for a drying fluid heated by said furnace, a dehydrator, means for discharging a liquid product into the upper end of said dehydrator in finely divided particles, means for forcing said drying fluid through said dehydrator for dehydrating said product, said dehydrator having a collecting channel around its lower end for receiving the dehydrated material and drying fluid, a collector, means for conducting said fluid and dehydrated material from said channel to said collector for separating the dehydrated product from said drying fluid and for collecting said product, a conduit for conducting said drying fluid from said collector, a conduit for conducting a portion of said drying fluid back to said channel for increasing the velocity of the drying fluid passing along said channel, and means for discharging fresh air into said channel for cooling the dehydrated material flowing along the same.

9. A method of dehydrating liquid products which comprises subjecting the products to indirect heat exchange with a heating medium to preliminarily concentrate the same, atomizing the concentrate and discharging the same into a current of hot air for dehydrating the product, separating the product from said hot air, mingling the hot air with the heating medium, and recirculating all of said hot air with said heating medium.

10. A method of continuously concentrating a liquid product which comprises subjecting the product to sub-atmospheric pressure and to a heating fluid of elevated temperature for removing moisture from said product, then lowering the temperature and pressure of the concentrate and conducting said moisture and said heating fluid into separate heat exchange relationship with said concentrate for further concentrating the same.

11. A method of concentrating a liquid product comprising applying heat thereto by means of a gaseous heating medium for reducing moisture contained therein to steam, applying said steam and medium in separate heat exchange relationship with the concentrate to further concentrate the same while reducing the pressure on the concentrate below that on the liquid product, whereby substantial vaporization of said concentrate is obtained.
